WALTER J. HERSCHEDE, OF CINCINNATI, OHIO, ASSIGNOR TO THE HERSCHEDE HALL CLOCK COMPANY, OF CINCINNATI, OHIO, A CORPORATION OF OHIO.

CHIME-STRIKING HAMMER.

1,205,202.

Specification of Letters Patent. Patented Nov. 21, 1916.

Application filed July 31, 1915. Serial No. 42,874.

To all whom it may concern:

Be it known that I, WALTER J. HERSCHEDE, a citizen of the United States of America, and resident of Cincinnati, county of Hamilton, State of Ohio, have invented certain new and useful Improvements in Chime-Striking Hammers, of which the following is a specification.

This invention relates to improvements in chime striking hammers and particularly to hammers for chime clocks, in which it is usual to employ a leather covering for the hammer face for the purpose of cushioning the blow given the chime by the hammer, in order to prevent the metallic sound of the metal hammer striking the metal chime.

An object of my invention is to produce a hammer for striking chimes, in which improved means are employed for securing the leather cushion at the end of the hammer.

A further object is to produce an improved chime striking hammer in which means are employed for positively centering, and maintaining the leather cushion taut at the end of the hammer with a uniform tension, so that the character of the blow struck by the hammer will always be uniform.

A further object is to produce an improved chime striking hammer in which the character of the blow struck by the hammer will be unaffected by changes in weather conditions.

These and other objects are attained in the hammer described in the following specification and illustrated in the accompanying drawings in which;

Figure 1 is a view of the back of the hammer. Fig. 2 is a view of the side of the hammer. Fig. 3 is a view of the front of the hammer. Fig. 4 is a sectional view taken on the line 4—4 of Fig. 1, certain interior parts being shown in elevation for convenience of illustration. Fig. 5 is a view similar to Fig. 4 with those parts shown in section which are shown in elevation in Fig. 4.

The hammer embodying my invention consists of an internally screw threaded collar 6, having an externally screw threaded plug 7 located therein, a leather cushion 8 secured in position by the plug and collar, a mounting spring 9, a washer 10, and a screw 11 passing through the washer, the

spring, and into the plug 7 to mount the hammer upon the spring. The collar 6 is screw threaded upon its interior for a portion of its length, the major portion of the remainder of its interior surface, having a straight bore 12 which extends adjacent to the end of the collar, the end of the bore being inclined to provide a reentrant tapering flange or shoulder 13. The outer surface of the collar is tapered from a point adjacent to the end of the internally screw threaded portion, to a point adjacent to the striking face of the hammer, at which point this tapered surface 14 is provided with a greater taper to produce a feather edge between the internal tapered surface 13 and the external tapered surface 15. The plug 7 is provided with screw threads for a portion of its length, substantially equal to the distance of the screw threads in the collar 6, and a straight cylindrical surface 16 for a portion of the remainder of its length, the plug terminating in a tapered surface 17 adjacent to its substantially flat end 18, the tapered surface and the flat end forming a truncated cone. The tapered surface of the plug and the internal tapered surface 13 of the collar are adapted to cooperate with one another in compressing the edges of the leather cushion 8 placed over the head of the plug 7, and to simultaneously stretch the leather and maintain it tightly against the end 18 of the plug 7, to produce a cushion having a cup-like formation. The mounting spring 9 for the hammer is provided with an aperture 20 and the plug 7 is provided with a registering aperture which is screw threaded, the screw threads being provided to receive the screw 11 which passes through an aperture 21 in the metal washer 10 and an aperture 20 in the spring for the purpose of securing the head comprising the collar 6 and plug 7, as well as the back comprising the washer 10, to the spring. The plug 7 is provided with a slot 22 at its screw threaded end to receive the blade of the screw driver so that the plug may be secured within the collar 6 for the purpose of securely fastening the leather cushion in position against the tapered surfaces 13 and 17 and the end surface 18 of the plug.

By means of my improved chime striking hammer I have overcome the objections found in hammers heretofore employed,

which utilize a turned metal head having a knob formed on one end for receiving the leather cushion, with a groove formed on the knob for receiving a binding wire which 5 passes over the leather for securing it in position. Such a construction is somewhat of a make-shift and renders the leather covering liable to bag or become too loose upon the knob with no means of tightening it 10 properly. In my improved construction it is merely necessary to remove the head comprising the collar 6 and the plug 7, and to tighten up the plug in the collar by means of a screw driver located in the slot 22. The 15 metal washer 10 is preferably made somewhat thick for the purpose of giving it weight to render the hammer sufficiently heavy to strike the chime properly. In addition to this the heavy washer balances the 20 hammer properly on each side of the spring.

In driving plug 7 into place it will not split and will stretch the leather evenly, and will neither warp nor become loose nor swell and change the thickness of the leather covering it. This results in a uniformity in 25 character of strike, and produces tones of unvarying quality.

Having thus described my invention, what I claim is:

- 30 1. In a chime striking hammer the combination of a collar, a metal plug mounted in the collar, a leather cushion mounted on the plug and held in position by the collar, a handle, a heavy metal washer, and a screw 35 mounted in the plug adapted to secure the handle between the plug, collar, and the washer.
2. In combination in a chime striking hammer, a hammer head, a handle, a heavy 40 washer, and means adapted to secure the handle between the washer and the head, said head comprising a collar having an inwardly tapered inner surface, a plug located in the collar and having an externally 45 tapered surface adapted to coöperate with

the tapered surface of the collar, a leather cushion mounted on the plug and held in position by the coöperating tapered surfaces of the plug and collar, and means formed externally of the plug and internally of the 50 collar adapted to secure the plug and collar together.

3. A chime striking hammer comprising a hammer head, a handle, a heavy washer, a means adapted to secure the handle between 55 the washer and head, said head consisting of a collar having an inner surface tapering inwardly to its outer end, a plug having an inwardly tapering outer surface, a cushion located between the tapered surfaces of the 60 plug and the collar, and means for securing the plug and collar together to clamp the cushion in position.

4. In a chime striking hammer, a hammer head consisting of a headed plug having an inwardly tapering outer surface, a collar having an inner surface tapering inwardly at its outer end, a cushion located between the tapered surfaces of the plug and collar, and means for securing the plug 70 and collar together to clamp the cushion in position over the head of the plug.

5. In a chime striking hammer, a hammer head consisting of a collar having an inner surface tapering inwardly at its outer 75 end, a headed plug having an inwardly tapered outer surface, a cushion located between the tapered surface of the plug and collar, and screw threads formed on the collar and plug for securing them together to 80 clamp the cushion in position over the headed end of the plug.

In testimony whereof, I have hereunto subscribed my name this 29 day of July, 1915.

WALTER J. HERSCHEDE.
